UNITED STATES PATENT OFFICE.

THEODORE AHLBORN, OF CHICAGO, ILLINOIS.

MIXING APPARATUS.

1,127,150.

Specification of Letters Patent.

Patented Feb. 2, 1915.

Application filed February 7, 1914. Serial No. 817,235.

To all whom it may concern:

Be it known that I, THEODORE AHLBORN, a citizen of the United States, residing at Chicago, in the county of Cook and State of Illinois, have invented certain new and useful Improvements in Mixing Apparatus, of which the following is a specification.

This invention relates to apparatus for mixing concrete and analogous material, and its object is to provide a mixer of simple and durable construction characterized by a rotatable drum, the axis of which is inclined, in which drum, at the bottom thereof, is located a cone which serves as a closure for the outlet or discharge opening of the drum, and also as a means for expediting the mixing process. Novel means for supporting the cone are provided, whereby the cone may be tilted to uncover the outlet, without stopping the drum.

In order that the invention may be better understood, reference is had to the accompanying drawings, in which—

Figure 1 is a side elevation of the apparatus; Fig. 2 is a rear elevation thereof; Fig. 3 is a vertical section on the line 3—3 of Fig. 2, and Fig. 4 is an elevation of the discharge spout of the mixing drum.

Referring specifically to the drawings, 5 denotes two channel beams which serve as sills for supporting the frame or base of the apparatus, the same comprising a base plate 6, side walls 7, a rear wall 8 and a front wall 9, all integral with the base plate. Between 15 these walls is mounted a rotatable mixing drum or vessel composed of a bowl-shaped lower part 10 and a lighter frustal upper part 11 suitably fastened together. The part 11 is open at its upper end through 20 which the material to be mixed is thrown. At its junction with the part 11, the part 10 has an external rim 12 the under side of which is toothed to form a gear ring 13. To the rear of the part 10, 25 on opposite sides thereof, below the axis of the drum, are located rotatable disks or rollers 14 journaled in suitable bearings on the walls 7. The disks have stepped peripheries to engage the smooth edge and top 30 portions of the rim 12. The mixing drum is so positioned that its axis is inclined; and the disks 14 are therefore located to act as a support for the drum to prevent the same from tilting downward. The drum is ro-

tated about its inclined axis by means of a 55 pinion 15 which is in mesh with the gear ring 13 on one side of the drum. The pinion is on a shaft 16 having a drive pulley 17 and journaled in a bearing standard 18. The pinion also serves as a lateral support 60 for the drum.

The bottom of the bowl-shaped part 10 has a central discharge opening from which extends a tapering spout 19, and at said discharge opening the wall of the bowl is thickened and shaped to form an external annular bearing shoulder 20 which is opposite a bearing ring 21 formed integral with a wall 22 rising from the base plate 6. The lower portion of the bearing ring connects 70 integrally with the wall 9. The wall 22 has an opening 23 to accommodate the spout 19, and a curved web 24 extends between the walls 9 and 22 for the purpose of a reinforcement.

The herein described integral construction of the supporting frame of the mixing drum makes a rigid and durable bottom support for the latter. The parts 20 and 21 are formed with raceways to hold anti-friction balls 25, and suitable means will be provided for lubricating the bearing.

In the bottom of the bowl part 10 of the mixing drum, at the discharge opening, is an annular depression 26 which forms a 85 seat for a hollow cone-shaped member 27 open at its base and having thereat a curled reinforced rim 28 which engages the seat. The side of the cone is slightly concave as shown in Fig. 3 to reduce its volume. The 90 axis of the cone is parallel to and coincides with the axis of the mixing drum, and from its apex projects a stem 29 having intermediate its ends a spherical enlargement 30. The stem and sphere are located in 95 a housing 31 which is made up of two parts bolted or otherwise fastened together to permit assemblage of the parts. In the housing is a seat for the sphere or ball 30, and above the seat is a recess 32 to accommodate 100 the projecting end of the stem 29. The width of the recess is such that the stem is prevented from moving laterally therein. Thus the stem can move only in a vertical plane, parallel to and coinciding with the 105 axis of rotation of the mixing drum, and the cone is constrained to swing in this plane only.

The housing 31 is carried by the lower end of a rod 33 extending down into the mixing drum through the upper open end thereof, and said rod is connected to and depends from the middle of a bail 34, the ends of which straddle the mixing drum and are pivoted at 35 in the side walls 7. The bail ends have continuations 36 carrying counterweights 37.

10 In the mixing drum are suitable mixing blades 38 secured to the walls thereof and projecting inward.

In operation, the cone 27 is positioned as shown in full lines in Fig. 3 to close the 15 discharge or outlet opening of the part 10 of the mixing drum. The material to be mixed may now be thrown into the drum, and the latter is then set in motion through the drive gearing hereinbefore described, 20 the drum being revolved about its inclined axis. The cone 27 is also free to turn by reason of the ball-and-socket bearing formed by the parts 30 and 31. To empty the drum, the bail 34 is pulled rearward, 25 whereupon, through its connection with the cone, the latter is tilted away from the outlet opening in the bowl 10, and the contents of the drum are then discharged through the spout 19. When the drum is 30 emptied, the bail is released, whereupon the weights 37 swing it back to restore the cone to its normal position. The cone can be tilted without stopping the drum, which facilitates the discharge. The turning point 35 of the cone is the lower portion of the base rim 28, from which point the pivots 35 of the ball are slightly offset, which allows the rim to move on the seat 26 and not wear the latter in one place only. The cone also 40 serves to hasten the mixing process by pushing the material back to the blades 38.

While the preferred embodiment of the invention has been shown and described, it is to be understood that many changes in the 45 structural details may be made without departure from the spirit and scope of the invention as claimed hereinafter.

I claim:

1. A mixing apparatus comprising an inclined rotatable drum having an outlet at 50 its lower end, and an annular seat surrounding the outlet, an axially located inwardly extending closure in the drum engaging said seat, and means for tilting said closure from 55 the seat.

2. A mixing apparatus comprising an inclined rotatable drum having an outlet at 60 its lower end, an axially located inwardly extending closure in the drum seating loosely over the outlet, and a tiltable support for the closure having a rotatable connection with the outer end thereof.

3. A mixing apparatus comprising an inclined rotatable drum having an outlet at 65 its lower end, and an annular seat surround-

ing the outlet, an axially located inwardly extending closure in the drum loosely engaging said seat, and a tiltable support for the closure having a rotatable connection with the outer end thereof.

4. A mixing apparatus comprising an inclined rotatable drum having an outlet at 70 its lower end, an axially located inwardly extending closure in the drum seating loosely over the outlet, and a tiltable support for the closure having a ball-and-socket connection with the outer end thereof.

5. A mixing apparatus comprising an inclined rotatable drum having an outlet at 75 its lower end, an axially located inwardly extending closure in the drum rotatably seating at its lower end over the outlet, a swinging member extending into the drum, and a bearing carried by said member and supporting the upper end of the closure.

6. A mixing apparatus comprising an inclined rotatable drum having an outlet at 80 its lower end, an axially located inwardly extending closure in the drum seating loosely over the outlet, a tiltable support for the closure having a rotatable connection with the outer end thereof, and means for guiding the closure to move in a vertical plane parallel to and coinciding with the axis of the drum.

7. A mixing apparatus comprising an inclined rotatable drum having an outlet at 85 its lower end, an axially located inwardly extending closure in the drum seating loosely over the outlet, a stem projecting axially from the outer end of the closure and having a sphere, a supporting member in the drum provided with a socket for the sphere and a recess for the stem, in which 90 said stem is held against lateral movement but free to swing in a plane parallel to the axis of the drum, and a swinging support 95 for said member.

8. A mixing apparatus comprising an inclined rotatable drum having an outlet at 100 its lower end, an axially located inwardly extending closure in the drum rotatably seating at its lower end over the outlet, a bearing in the drum supporting the upper 110 end of the closure, and a pivoted member outside the drum having a connection with the bearing for tilting the closure toward and from the outlet.

9. A mixing apparatus comprising an inclined rotatable drum having an outlet at 115 its lower end, an axially located conical closure in the drum, the base of the cone seating over the outlet and its apex extending inward, and a pivoted member carrying a bearing for supporting the apex of the 120 cone.

10. A mixing apparatus comprising an inclined rotatable drum having an outlet at 125 its lower end, an axially located conical closure in the drum, the base of the cone 130

seating over the outlet and its apex extending inward, a bearing in the drum supporting the apex of the cone, and a pivoted member outside the drum having a supporting connection with the bearing.

11. A mixing apparatus comprising an inclined rotatable drum having an outlet at its lower end, an axially located conical closure in the drum, the base of the cone seating over the outlet and its apex extending inward, and a tiltable support for the cone having a bearing for the apex thereof.

12. A mixing apparatus comprising an inclined rotatable drum having an outlet at its lower end, an axially located conical closure in the drum, the base of the cone seating over the outlet and its apex extending inward, and a tiltable support for the

cone having a ball-and-socket connection with the apex thereof.

13. A mixing apparatus comprising an inclined rotatable drum having an outlet at its lower end, an axially located conical closure in the drum, the base of the cone seating over the outlet and its apex extending inward, a stem projecting from the apex of the cone and having a sphere, a housing supporting the stem and the sphere, and a swinging support for the housing.

In testimony whereof I affix my signature in presence of two witnesses.

THEODORE AHLBORN.
